CASSETTE REEL MOTION INDICATOR

John M. Baker, San Clemente, Calif., assignor to Cassette Magnetics Corporation, doing business as American Cassette Corporation, Inglewood, Calif.

Filed Nov. 12, 1971, Ser. No. 198,491

Term of patent 14 years

Int. Cl. D14—01

U.S. Cl. D26—14 B

FIG. 4.

FIG. 1.

FIG. 5.

FIG. 6.

FIG. 2.

FIG. 3.

FIG. 1 is a front view of a cassette reel motion indicator showing my new design;

FIGS. 2 and 3 are side views thereof;

FIG. 4 is a top plan view thereof;

FIG. 5 is a bottom plan view thereof; and

FIG. 6 is a rear view thereof.

The side and back not shown are similar to the respective side and front illustrated.

I claim:

The ornamental design for a cassette reel motion indicator, as shown and described.
